UNITED STATES PATENT OFFICE.

LESTER M. WENTLING, OF FOXBURG, PENNSYLVANIA, ASSIGNOR OF ONE-HALF TO CHARLES L. GOUGHLER AND EDWARD RUMBAUGH, OF FOXBURG, PENNSYLVANIA, LLOYD STEWART, OF PARKERS LANDING, PENNSYLVANIA, AND CHARLES W. PFAFF, OF EMLINGTON, PENNSYLVANIA.

TIE PLATE.

Application filed January 25, 1923. Serial No. 614,813.

To all whom it may concern:

Be it known that I, LESTER M. WENTLING, a citizen of the United States of America, residing at Foxburg, in the county of 5 Clarion and State of Pennsylvania, have invented new and useful Improvements in Tie Plates, of which the following is a specification.

The object of the invention is to provide 10 a railroad tie plate which will serve as a rail chair or support for receiving the rail base and securing the same to the tie to prevent displacement in a direction permitting spreading of the rails while avoiding the 15 risk of splitting the ties, and which at the same time may be secured to the tie with the minimum number of fastening means; and with this object in view the invention consists in a construction and combination 20 of parts of which a preferred embodiment is shown in the accompanying drawings, wherein:—

Figure 1 is a perspective view of a tie plate embodying the invention.

25 Figure 2 is a plan view of the same showing a section of rail in place on the plate.

The tie plate 10 is provided with a rail seat 11 which is bounded at opposite sides by upstanding shoulders 12 formed by the 30 inner edges of thickened portions or bosses 13 preferably integral with the plate and having downwardly and outwardly beveled upper surfaces. In the inner edges of these bosses are formed spike holes 14, with those 35 in one boss arranged in staggered relation transversely with those in the other boss to the end that no two spikes may penetrate the tie to which the plate is secured on a common longitudinal line, and therefore to 40 the end that the tendency to split the tie by the driving of the spikes may be minimized.

A supplemental spike hole 15 is also preferably formed in the thickened or boss carrying portion of the plate at that end of the 45 latter which projects outward from the line of the track rail or in other words is outside of the line of the track, for the reception of a spike to prevent the outward movement of the plate and therefore the spreading of the 50 rails. This supplemental spike hole is preferably arranged opposite the interval between the main spike holes of the same boss or enlargement and on a different longitudi-

nal line of the tie from the spike holes of the other boss in the same plate.

The shoulders formed by the inner edges of the enlargements or bosses of the plate obviously constitute fixed abutments for the bearing of the opposite edges of the rail base indicated at 16, and the proper seating 60 of the rail base in the space between the shoulders is insured by the spikes which are driven through the main spike holes 14 and which communicate at their inner sides with the seat provided for the reception of the 65 rail base to the end that the heads of the spikes may bear directly upon the edges of the rail base. Also the shoulders or fixed abutments 12 constitute means precluding the lateral movement of the rails in either 70 direction when the same expand or contract or when they are subjected to strains tending to move them laterally at the ends such as are due to passing trains. Obviously the tie plates can be made in various sizes with 75 seats and fixed abutments arranged to suit rail bases of various dimensions. The under face of the tie plate is smooth and unobstructed, obviously permitting the plate to engage with the upper face of the tie 80 throughout its full area, hence preventing the collection of foreign matter and frost thereunder. The spike receiving openings are immediately adjacent where the enlargements merge into the shoulders and since 85 the openings break into the seat, the heads of the spikes may be directed inwardly and toward the opposite sides of the track rail base, thereby constituting means to protect and prevent outward deflection of the heads 90 from the opposite remote edges of the track rail base. Furthermore, the spike receiving openings are transversely staggered, thereby minimizing the tendency of the spikes to 95 split the tie and thereby preventing the tie plate from twisting in case the spikes loosen.

The supplemental spike receiving opening formed through one of the enlargements is disposed offset relatively to certain of the first openings to receive additional securing means, thereby preventing twisting of the tie plate in case the other fastening means loosen and become detached.

Having described the invention, what is claimed as new and useful is:—

As an article of manufacture, a tie plate

provided with a track rail base receiving seat and opposite terminal enlargements, and opposed shoulders caused to be formed by the enlargements and constituting the 5 thickest portion of the tie plate and also laterally bounding the seat, the under face of the tie plate being smooth and unobstructed, said tie plate having spike receiving openings immediately adjacent where the enlargements merge into the shoulders, said spike receiving openings breaking into the seat, whereby the heads of the spikes may be directed inwardly and toward the opposite sides of the track rail base, the walls of 10 the openings acting to prevent the spikes from working laterally away from the track

rail base, said spike receiving openings being transversely staggered, thereby minimizing the tendency of the spikes to split the tie and thereby preventing the tie plate 20 from twisting in case the spikes loosen, said tie plate being supplemented with an additional spike opening formed through one of the enlargements intermediate of and disposed offset relatively to certain of the first 25 openings to receive additional securing means and thereby prevent twisting of the tie plate in case the other fastening means loosen and become detached.

In testimony whereof I affix my signature,

LESTER M. WENTLING.
